UNITED STATES PATENT OFFICE.

OTTO E. DENIVELLE, OF MOUNT VERNON, NEW YORK, ASSIGNOR TO LOUIS AMBERG & SON, OF NEW YORK, N. Y., A CORPORATION OF NEW YORK.

DESIGN FOR A GARMENT HANGER.

60,514.

Specification for Design.

Patented Mar. 7, 1922.

Application filed June 7, 1921. Serial No. 475,728. Term of patent 3½ years.

To all whom it may concern:

Be it known that I, OTTO E. DENIVELLE, a citizen of the United States of America, residing at Mount Vernon, in the county of Westchester and State of New York, have invented a new, original, and ornamental Design for a Garment Hanger, of which the following is a specification, reference being had to the drawing forming a part thereof.

I claim:

The ornamental design for a hanger as shown.

OTTO E. DENIVELLE.
